UNITED STATES PATENT OFFICE.

MARK W. MARSDEN, OF PHILADELPHIA, PENNSYLVANIA.

SYSTEM FOR COOLING AND DISPENSING BEVERAGES.

968,378.

Specification of Letters Patent. Patented Aug. 23, 1910.

Application filed June 23, 1909. Serial No. 503,901.

To all whom it may concern:

Be it known that I, MARK W. MARSDEN, a citizen of the United States, and a resident of Philadelphia, in the county of Philadelphia and State of Pennsylvania, have invented a new and useful System for Cooling and Dispensing Beverages, of which the following is a specification.

This invention relates to systems for cooling and dispensing beer, ale, porter, and other beverages on draft.

One of the principal objects is to provide an installation that shall be absolutely sanitary.

Another object is to provide an installation that shall be simple in construction and mode of operation and which may be easily set up in the place of old systems without dismantling the bar.

Another object is to provide for cooling beverages with but a fraction of the quantity of ice heretofore required.

Another object is to provide an air circulating and cooling system wherein the beverage connections are substantially enveloped by air cooled passages and wherein some of the air is used for forcing purposes.

There are further objects whereof some are obvious and others will be referred to with more particularity in the course of the detailed description.

The nature, characteristic features and scope of the invention will be more readily understood from the following description taken in connection with the accompanying drawings, forming a part hereof, wherein—

Figure 1, is a view principally in perspective showing the general arrangement of the units. Fig. 2, is a sectional view through the bar or ice box. Fig. 3, is a sectional view of the lower cylinder showing accessories and contents thereof. Fig. 4, is a sectional view of the beer rod and its connections; and Fig. 5, is a sectional fragmentary view of the beer rod.

Referring to the drawings 1, is a bar of usual construction whereof the cabinet or ice-box 2, is equipped with air containing tanks or cylinders 3, whereof the number 50 may vary according to the size of the ice-box or other features of the installation. For convenience and also because it is desirable to have them immersed in the ice water that accumulates in the ice-box they 55 are laid in the bottom thereof. Said tanks or cylinders are connected in series or inter-

communicate, as at 4, and one of them has a valved inlet 5, for air of the desired temperature and compression, the air compressor not being shown. The air circulating through the battery of tanks has its temperature further reduced and passes through a reduction valve 6, into a jacket or casing 7, that incloses a plurality of beverage conduits or passages 8. The jacket or 60 casing 7, extends down to the cellar or wine room or to a point contiguous the cask or barrel containing the beverage and is connected by a suitable coupling 9, with a double tank or distributing cylinder 10, into 65 which the air discharges. Said cylinder is equipped with a number of couplings or openings 11, one for each beverage conduit or connection 8, and the latter passes through the respective coupling and a clamp 75 12, connects it to the valve 13, of a beer rod 14. The latter is almost entirely inclosed by a jacket or casing 15, and the space between the two constitutes an air chamber 16, that is separated by plates or baffles 17, Fig. 80 5, with openings 18, near the bottom so that the air passes down one side and up the other.

19, indicates a bung, which is carried by the rod and which coöperates in the well 85 known manner with the bushing 20, on the barrel or cask to secure a tight joint. There is an annular air space or chamber 21, in the bung, which air space communicates with the air chamber 16, of the rod by a vent 22, 90 and at 23, there is some clearance between the bung and the jacket 15, to permit air to pass into the barrel or cask for forcing purposes.

The outer ends of the couplings 11, are 95 stopped by disks or washers 24, so that a consequent air space 25, is provided which has a vent 26, whereby communication may be had between the air space 25, and the air space 22, in the bung, by means of a valved 100 connection 27. The air jacket or casing 15, on the beer rod has a vent or outlet 28, and a valved connection 29, connects it with an air exhaust cylinder 30, that is equipped with a relief valve 31. The valve 31, is set 105 at a pressure lower than that taken care of by the valve 6, so that air is constantly escaping and followed by fresh supplies of cold air. Said air exhaust cylinder and the tank 10, are equipped with water supply 110 and outlet connections, indicated at 32, 33, and 34, 35, respectively, so that flushing may

be resorted to from time to time as may be necessary to keep the system clean and sanitary.

The connection in the ice-box or cabinet 5 between the beverage conduits or passages 8, and the draw cocks or faucets 36, may be straight connections as at 37, or coils, as at 38. Both types of connections are shown in Fig. 1.

10 It is manifest from the foregoing description that with a minimum quantity of ice and by the use of air at an appropriate pressure, I am enabled to cool and dispense beer, ale, porter, and other beverages more 15 economically than has heretofore been accomplished and most important of all under perfect sanitary conditions.

Having described the nature and objects 20 of my invention, what I claim as new and desire to secure by Letters Patent is:—

1. The combination of a draw-box adapted for ice, a tank therein for containing air under pressure, a beer keg, a beer rod penetrating the same and having a surrounding 25 air jacket equipped with an exhaust, a bung having an air chamber communicating with said jacket and having a separate outlet for supplying air to the keg for forcing purposes, and a connection intermediate the 30 bung and air pressure tank including means for regulating the pressure, substantially as described.

2. In combination, a beer keg, a beer rod penetrating the same and having an air-cooled jacket, a bung carried by the rod and having an air chamber communicating with both the jacket and the keg, a draw-box and its accessories, a draft connection intermediate the rod and box, an air-cooled 35 jacket or casing substantially inclosing said connection and communicating with said air chamber, means for directing cold air at an appropriate pressure into said casing, and suitable exhaust connections communicating 40 with the rod jacket, substantially as described.

3. In combination, a beer keg, a beer rod

having an air jacket, a bung having an air chamber that communicates with both the air jacket and the keg, a draft connection 50 intermediate the rod and the box, an air pressure holder in the draw-box, an insulated valved connection intermediate said holder and air chamber, and a receiver adapted and arranged to take air from the 55 air jacket and equipped with a relief valve, substantially as described.

4. The combination of a cold air conduit extending from the bar to a point contiguous the beer keg, draft connections traversing 60 said conduit, a beer rod terminating said connections and having an air-cooled chamber or jacket, and a bung carried by the rod and having an air chamber adapted and arranged to take air from said conduit and supply some to the keg for forcing purposes and some to the air jacket, said jacket having a suitable exhaust so as to maintain a substantially constant circulation of cold air, substantially as described. 70

5. The combination of a draw-box adapted for ice, a tank therein for containing air under pressure, a second or distributing tank, means for intermittently discharging cold air from the first tank into the second, 75 a beer keg, a beer rod penetrating the same, and having an air jacket equipped with an inlet and an outlet, a bung having an air chamber that has an insulated connection with the second tank and supplies air to the 80 keg for forcing purposes and air to the jacket for cooling purposes, automatic exhaust mechanism associated with the outlet of the jacket, and an insulated draft connection extending from the rod to the draw- 85 box, substantially as described.

In testimony whereof I have hereunto signed my name to this specification in the presence of two subscribing witnesses.

MARK W. MARSDEN.
